UNITED STATES PATENT OFFICE.

FRIEDRICH HAUPTMEYER, OF ESSEN, GERMANY, ASSIGNEE TO FRIED. KRUPP AKTIENGESELLSCHAFT, OF ESSEN-ON-THE-RUHR, GERMANY.

STAMP FOR THIN SHEET-METAL PLATES, SUCH AS DENTAL PLATES AND THE LIKE.

1,424,406.

Specification of Letters Patent. Patented Aug. 1, 1922.

Application filed February 14, 1921. Serial No. 444,980.

To all whom it may concern:

Be it known that I, Dr. FRIEDRICH HAUPTMEYER, residing at Essen, Germany, a citizen of the German Republic, have invented 5 a certain new and useful Improvement in Stamps for Thin Sheet-Metal Plates, such as Dental Plates and the like (for which I filed application in Germany on December 1, 1919), of which the following is a specification.

This invention relates to stamps for thin sheet metal plates, such as dental plates and the like, and the object of the invention is to impart the desired form to such thin 15 sheet metal plates in a single operation, without any creases forming in the work, the formation of such creases being undesirable and to be avoided even when the hardest material is employed, e. g. steel, 20 particularly that class of chromium-nickel steel which possesses a very high power of resistance to attack by acids.

The invention as applied to the manufacture of dental plates will be described with 25 reference to the diagrams in which—

Figure 1 is a central vertical section through the stamp, the blank and the die, in the position at the commencement of the stamping operation,

30 Figure 2 is a corresponding section during a period of the stamping operation and

Figure 3 is a corresponding view in the position at the completion of the stamping operation.

35 A denotes the die and B the sheet metal which forms the blank. The stamp C at the part which comes in contact with the blank is of a plastic substance, such as lead for example. This part of the stamp C is so 40 formed that during the course of the work the blank B is clamped as soon as possible at the upwardly projecting edges a^1 of the die between the stamp and the die, as is shown in particular in Figure 2, the stamp 45 being so formed that at the commencement of the stamping operation it is in contact

with the blank B only between the edges a^1 of the die A.

During the course of the stamping operation the stamp adapts itself, owing to its 50 plasticity, more and more to the form of the die (see Figures 2 and 3) and the stamp becomes so altered in shape during the stamping operation that before the completion of the stamping operation the blank B 55 is firmly gripped between the stamp C and the edges a^1 of the die A for the purpose of preventing the formation of creases. At the same time the centre of the sheet metal B is gradually pressed into the hollow part 60 of the die. The sheet metal B is thus drawn through inwards at the raised edges a^1 of the die A to correspond to the increasing requirement for material between the die and the stamp overcoming as it does so the 65 grip produced by the pressure at the edges a^1 of the die.

In comparison with known similar arrangements the clamping of the sheet metal B at the raised edges of the die which im- 70 parts the shape to the blank secures the advantage that the stamping can be carried out in a single operation without creases being formed in the blank, even when this latter consists of a material of the greatest 75 hardness and strength.

Claim.

A press for thin plates comprising in combination a concave die member having a raised rim and a ductile stamp tapering to- 80 wards its front end and having on its front end a cross-sectional area smaller than the area limited by said rim, said ductile stamp being adapted to freely expand around its whole circumference in lateral direction. 85

The foregoing specification signed at Essen, Germany, this 4th day of December, 1920.

DR. FRIEDRICH HAUPTMEYER.
